UNITED STATES PATENT OFFICE.

VIRGIL SIDNEY DOWNING, OF JACKSON, MISSISSIPPI.

BOAT CONSTRUCTION.

1,408,178.

Specification of Letters Patent. Patented Feb. 28, 1922.

Application filed November 20, 1920. Serial No. 425,474.

To all whom it may concern:

Be it known that I, VIRGIL SIDNEY DOWNING, a citizen of the United States, and a resident of Jackson, in the county of Hinds and State of Mississippi, have invented certain new and useful Improvements in Boat Constructions, of which the following is a specification.

My invention relates to boat construction, and a purpose of my invention is the provision of a boat having an air duct and air channels formed in its hull which are so shaped and positioned as to effect a lifting and propelling action to the boat when air is forced rearwardly through the duct. The construction of the hull is such that the air as discharged from the duct is caused to provide a film of air beneath the rear end portion of the boat and upon which such portion is adapted to ride so that in conjunction with the lifting action upon the forward end of the boat by virtue of the air traversing the duct, the boat as an entirety is caused to ride substantially upon a film of air.

I will describe one form of boat embodying my invention and will then point out the novel features thereof in claims.

In the accompanying drawings:

Figure 1 is a view showing in top plan, with portions partly broken away, one form of boat embodying my invention.

Figure 2 is a vertical longitudinal sectional view of the boat shown in Figure 1.

Figure 3 is a front end elevation of the boat shown in the preceding views.

Figures 4, 5, 6, and 7 are transverse vertical sectional views taken on the lines 4—4, 5—5, 6—6 and 7—7 respectively of Figure 2.

Figure 8 is an enlarged fragmentary detail view showing the means for connecting or disconnecting the propeller to or from the motor shaft.

Similar reference characters refer to similar parts in each of the several views.

Referring specifically to the drawings, my invention in its present embodiment consists of a hull designated generally at H having a forward round bottom portion h and a flat rear bottom portion h', the latter bottom portion being disposed in a plane above that of the forward bottom portion. As shown in Figures 1 and 2, the hull H is formed centrally thereof with a longitudinally extending duct D through which air is adapted to be forced in effecting a lifting of the forward end of the hull and a propulsion of the boat.

As illustrated to advantage in Figure 2, the forward end of the duct D is open for the admission of air thereto and is disposed at the upper end of the bow of the hull so that it is at all times disposed at a safe distance above the water-line to preclude the entrance of water into the duct. The duct D is inclined rearwardly and downwardly from its forward end to its rear end, the latter end extending through the bottom of the hull at the confronting ends of the bottom portions h and h'. As seen in Figure 3, the forward end of the duct is of substantially rectangular form in cross section. From this point rearwardly, the duct gradually increases in cross sectional area until it reaches a medial portion indicated at 15. From this portion to the rear end of the duct the cross sectional area gradually decreases until the rear or outlet end of the duct is of an area less than one-half of the area of the medial portion 15. This outlet end is adapted to be controlled by a door 16 hingedly supported upon the hull and provided with a coiled spring 17 which normally urges the door to closed position and against a stop 18 so that the passage of water upwardly into the duct is prevented.

By reference to the vertical sectional views taken through the hull, it will be clear that the forward end portion of the duct is of rectangular form, such end portion merging into a tubular or circular portion as clearly shown in Figure 5, and this tubular portion merges into a semi-circular portion which is continued to the rear or exit end of the duct. The exit end of the duct is of semi-circular form as clearly shown in Figure 6, and it will be understood that the door 16 is of a corresponding shape.

As shown in Figures 1 and 2, the upper forward side of the duct D is formed with two walls 19 which are inclined forwardly toward each other where they finally merge into a single wall. These walls are formed with a plurality of openings in which are placed short pipe sections 20 that provide air channels. These air channels are in direct communication with the duct D, and through such channels air is admitted to the duct from its upper side for a purpose which will be hereinafter described.

As shown in Figures 1 and 2, a gasoline motor M is supported within the medial portion of the duct D upon beams 21. The motor M is of conventional form and is

adapted to drive a propeller P which is vertically positioned within the duct and is adapted to be rotated in such direction as to force air rearwardly through the duct. The 5 propeller P is supported on a counter shaft 22 which is adapted to be operatively connected to the motor shaft through the medium of a conventional form of clutch C. The clutch C is actuated by an actuating lever 10 L operatively connected to the clutch through the medium of a link 23 and a lever 24 fulcrumed on a standard 25. The lever L is suitably positioned in the pit T formed in the hull so as to be readily actuated by the 15 operator. A steering wheel S is provided which is operatively connected through the medium of cables 26 to a water rudder R and an air rudder R' both of which are supported for oscillating movement upon a 20 shaft 27.

In the operation of the boat, the propeller P when rotated in the proper direction creates a draft of air of great intensity rearwardly through the duct D, the air entering 25 the duct through the forward end and through the channels and finally exiting through the rear end of the duct, it being understood that the current of air is of sufficient intensity to swing the door 16 to open 30 position against the tension of the spring 17. When the draft of air traverses the duct D, it will be clear that the propeller P functions as an air propeller so as to propel the boat through the water. The air entering the 35 duct D through its forward end and through the air channels impinges upon the walls of the duct and because of the particular contour of the duct this draft of air is caused to impart a lifting action to the forward portion 40 of the boat which as a result elevates the forward end of the boat clear of the water. As the air is discharged from the rear end of the duct D it passes beneath the rear bottom end portion h' of the hull, and 45 because this bottom portion is disposed in a plane above that of the forward end portion h, it will be clear that a film of air is continuously provided beneath the bottom h' upon which the stern end of the boat is supported when travelling. The lifting action 50 imparted to the forward end of the boat naturally tends to move the rear end of the boat downwardly, but because of the film of air continuously formed beneath the stern end of the boat, it will be clear that such 55 film of air is compressed to a degree but not displaced so that the hull throughout its entire length is substantially free of the water when travelling at or above a predetermined 60 speed.

It is to be particularly noted that the motor M being positioned within the duct D is exposed to the air traversing the duct so that such air is utilized as a cooling medium for the engine. It is to be further

noted that because of the several air channels formed in the upper part of the duct, the air passing inwardly through such channels effects a pronounced lifting action to the forward end of the boat which in conjunction with the lifting action obtained as a result of the air impinging upon the upper side of the duct insures the lifting of the forward end of the boat from the water when the boat is travelling at a requisite speed. Because of the fact that the rear end of the duct D is constricted and curved downwardly from the medial portion, it will be manifest that the action of the propeller upon the body of air so trapped will impart a pronounced forward movement to the boat, thus providing an air propelling medium of maximum power efficiency.

Although I have herein shown and described only one form of boat construction embodying my invention, it is to be understood that various changes and modifications may be made herein without departing from the spirit of the invention or the spirit and scope of the appended claims.

What I claim is:

1. A boat including a hull, and an air duct formed in the hull and extending rearwardly and downwardly from the bow end of the hull to and through the bottom thereof at a point in the rear of the medial portion of the hull, a motor positioned within the duct, and a propeller vertically positioned within the duct and operatively connected to said motor.

2. A boat including a hull, an air duct formed in the hull and extending rearwardly and downwardly of the bow end to and through the bottom of the hull at a point in the rear of the medial portion of the hull, said duct being tapered from a point medially of its ends to its ends.

3. A boat including a hull, an air duct formed in the hull and extending rearwardly and downwardly of the bow end to and through the bottom of the hull at a point in the rear of the medial portion of the hull, said duct being tapered from a point medially of its ends to its ends, a motor positioned within the duct at its medial portion, and a propeller operatively connected to the motor and vertically positioned within the medial portion of the duct.

4. A boat including a hull, and an air duct extending rearwardly from the boat and downwardly to and through the bottom of the hull at a point in the rear of the medial portion of the hull, said duct being of angular cross section at its forward end, merging into its tubular portion of larger cross sectional area at its medial portion and finally terminating in a semi-tubular portion of smaller cross sectional area at its rear end.

5. A boat including a hull, and an air duct

extending rearwardly from the boat and downwardly to and through the bottom of the hull at a point in the rear of the medial portion of the hull, said duct being of 5 angular cross section at its forward end, merging into its tubular portion of larger cross sectional area at its medial portion and finally terminating in a semi-tubular portion of smaller cross sectional area at its 10 rear end, a motor within the tubular portion, and a propeller operatively connected to the motor and vertically positioned within the tubular portion.

6. A boat including a hull, an air duct 15 extending rearwardly from the boat and inclined downwardly to and through the

bottom of the hull, and a plurality of air channels formed in the upper wall of the duct and communicating with the duct.

7. A boat including a hull, an air duct 20 extending rearwardly from the boat and inclined downwardly to and through the bottom of the hull, a plurality of air channels formed in the upper wall of the duct and communicating with the duct, a motor in the 25 duct, and a propeller within the duct and adapted to be operatively connected to the motor to rotate in a direction to draw air rearwardly through the duct and downwardly of the air channels.

VIRGIL SIDNEY DOWNING.
